UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

TRUCK SIDE FRAME.

1,364,491.

Specification of Letters Patent.

Patented Jan. 4, 1921.

Application filed December 15, 1919. Serial No. 344,769.

To all whom it may concern:

Be it known that I, GEORGE G. FLOYD, a citizen of the United States, residing at Chicago, in the county of Cook and State of Illinois, have invented certain new and useful Improvements in Truck Side Frames, of which the following is a specification.

This invention relates to truck side frames.

One object of the invention is to provide a truck side frame in which the stresses are more evenly distributed and balanced than heretofore has been the case, and whereby such frame is materially strengthened at critical points without increasing the weight of the frame.

Another object is to provide an integrally formed truck side frame adapted to meet the various requirements under severe service conditions.

These and other objects are accomplished by means of the truck side frame shown on the accompanying sheets of drawings, in which—

Figure 1 is a side elevation of my improved side frame;

Fig. 2 is a top plan view of same;

Fig. 3 is a bottom plan view of same;

Figs. 4, 5, 6, 7, 8 and 9 are enlarged sectional views taken, respectively, in the planes 30 of lines 4—4, 5—5, 6—6, 7—7, 8—8 and 9—9 of Fig. 1;

Fig. 10 is a vertical longitudinal sectional view of my improved side frame; and,

Fig. 11 is a side elevation of an ordinary 35 cast steel side frame shown somewhat diagrammatically and illustrating various stresses set up in the frame when loaded.

The cast steel side frame is rather a complicated truss structure. It is subject to a 40 direct vertical load carrying the weight of the car and its lading, which load is received through the bolster springs. This direct loading is accentuated by the action of the bolster springs.

The side frame also receives a transverse 45 load delivered in the nature of shocks or blows occasioned by the longitudinal shifting of the truck bolster which delivers the shocks or blows to the side frame through 50 the column guides of the bolsters and of the side frame.

The side frame also is subjected to a twisting or torsional load when the car strikes or rounds a curve. This load is especially

severe if the spring plank connecting the 55 two side frames is riveted securely thereto.

In the cast or integrally-formed side frame in which all the various members of the truss are joined rigidly, the various direct loads which produce direct stresses also 60 produce secondary or induced stresses. At some points on the casting the secondary stresses are greater and more serious than the primary stresses. Some of the portions of the casting are subject to two primary 65 stresses and in addition several secondary stresses. In adding various stresses algebraically, it is found that at several points in the frame all the stresses which localize at these points happen to be plus or tension 70 stresses with no corresponding minus or compression stresses to lower the average 75

Referring particularly to Fig. 1 of the drawings, it will be noted that the side frame there disclosed includes a compression member 12 which extends substantially from end to end of the casting. The compression member is connected to the tension member 13 at the ends of the latter and also at the middle by two columns 14. The tension 80 member 13, from a stress point of view, may properly be divided into three elements; one being that part immediately under the bolster opening and extending between the lines C—D and C'—D', and which hereafter 85 will be referred to as part 15. The other two elements 16 extend upwardly in oblique lines from the lower ends of the columns 14 to the compression member 12 and connect with the latter at the ends of the casting 90 over the supports or journals S. The load P transmitted through the bolster springs, is delivered to the side frame at the point A, or in the middle of the upper surface of the tension element 15.

This portion 15 of the tension member 13 performs two functions: First, it acts as a beam of a length corresponding to the distance between the columns 14 to carry the load P applied at A, and in performing this function it is subject to ordinary bending stresses, which produce flexure or depression, the compression stresses being in the upper portion of element 15 and tension stresses in the lower portion of said element; 100 secondly, element 15 acts as a tension member and accordingly is subject to tension stresses in being a part of the main tension 105

member. Therefore, the element 15 is subject to bending stresses and direct tension stresses. The inclined portions 16 of the tension member connect the ends of the beam element 15 to the ends of the compression member along the line K—L, and are also subject to bending stresses in addition to the direct tension stresses, the former being occasioned because of the integral structure 5 of the casting, as distinguished from a structure of like character in which the members are connected by pin joints.

Referring particularly to Fig. 11, it will be noted that an ordinary cast steel side frame is shown which illustrates in an exaggerated manner the deformation of this casting under load, the load P being applied, as above mentioned, at the point A, and the reaction being at the points of support S. The tension element 15 will deflect or bend under this load, and the columns 14 will be distorted by this bending, the deformation in all parts of the frame being indicated by the full lines. The end 20 of the frame from the point K to the point of support S is found to be a short beam subject to bending stresses in carrying the load from point K to point S, and there is, therefore, a resultant upbending or turning 25 movement of the ends of the frame.

The downward deflection of the beam or tension element 15 and the upward deflection of the short beams immediately over the supports S—S produce in the inclined tension member portions 16 reverse bending 30 stresses which are in addition to the straight tension stresses, the latter stresses being due to the truss action of the casting as a whole. This reverse bending action 35 may be illustrated best by assuming that the inclined tension member portions 16 are sawed in two on the line I—J and the casting loaded at A and supported at the points S. Under such conditions, the sawed ends 40 will assume an offset position at the line I—J, as shown by dotted lines in Fig. 11.

In view of the fact that these sawed elements move relatively to each other into an offset position, bending stresses in the inclined portions 16 of the tension members 45 at the points K—L and G—H are eliminated. After the casting has assumed this offset position, let the offset ends be moved toward each other by some external force 50 to the extent that said ends register or are brought into alinement. Immediately bending stresses are developed in these inclined elements 16. In the offset positions, these two sawed portions might be considered 55 short beams fixed at one end at K—L and at the other end at G—H. Therefore, a flexure or deflection of the outer ends of these sawed portions or beams would produce maximum stresses at the fixed ends K—L 60 and G—H. There would be tension stresses 65

at G and K and compression stresses at H and L. But as this inclined portion of the truss structure also is subject to tension stresses from the truss action, adding these two stresses algebraically gives high tension stresses at G and K and very low stresses at H and L, which low stresses may be either tension or compression, depending upon whether or not the tension in the member from the truss action is greater or less 70 than the compression in the member from bending. While it is impossible, of course, for the inclined portions 16 of the tension member to be offset as hereinabove mentioned, the force or tendency is still there 75 and is the reason for the bending stresses at G—H and K—L. These bending stresses are neutral at some point between G—H and K—L, as, for example, along line I—J. Therefore, at the neutral point I—J, this 80 tension member element 16 is subject only to direct truss action tension stresses.

By developing a method of loading and testing such castings in a manner giving results similar to actual service conditions and 85 by the use of delicate extensometers, with which it is possible to measure the slightest stretch or shrinkage of the metal in any portion of the casting, I have been able to determine and measure the actual tension and 90 compression stresses in these castings, and such tests confirm the theoretical calculations that the points of highest stresses or critical points of the average size frame are 95 at B, G and K.

As mentioned above, the tension element 15 is subject to both bending stresses, with compression at A and tension at B, and also subject to straight tension stresses over the whole section from the truss action. If these 100 two stresses are approximately equal and are distributed equally, adding same algebraically, there would be a zero stress at the point A and a double tension stress at the point B, therefore making point B the critical point 105 in tension member section 15. By the same procedure, in adding algebraically the sum of the stresses from the truss action and the compression and tension stresses from the bending, it is found that the critical points 110 or double tension points are at G and K, while there may be zero stress points at H and L.

The line I—J, which is approximately half way between the lines G—H and K—L, 115 is neutral as to bending stresses in this member. The measured stress at I—J represents only the straight tension stress in this section resulting from the truss action of the entire casting. The difference between this 120 average in tension stress at I—J and the stresses at G—H and K—L are secondary or bending stresses.

As mentioned above, the points of high stress in the side frame are B, G and K. The 125

reasons for high tension stress at B will be considered a little more thoroughly at this point. Considering the beam section element 15 of the tension member alone and its composite loading, it is found that there are three distinct stresses acting upon the beam in side frames as produced heretofore. First, there is the simple load P acting at point A, it being understood that the beam is supported at its outer points D—D'. This load causes compression at A and tension at B. Second, there is tension as a result of the truss action which will be considered to be exerted on the longitudinal central line of the beam section 15. This tension accordingly will be exerted uniformly throughout the section of the beam 15, thereby adding to the tension at B and reducing the compression a certain amount at A. However, there is a third stress because as side frames are constructed the tension caused by the truss action of the side frame is not along the longitudinal central axis of the beam 15, but, as a matter of fact, is considerably below same. The result, therefore, is a further bending action of the beam 15 in the same sense as caused by load P. This means that the compression at A is increased and the tension at B is increased. In all three stresses it will be seen that the tension at B is increased. It will be understood, therefore, that if the third stress or tension can be exerted above the longitudinal central axis of beam 15, the compression at A will be reduced, and more important still the tension at B will be reduced, also the bending stresses at G and K will be decreased.

The reasons why points G and K are high stress points may be analyzed from another standpoint. In Fig. 11, I have drawn line F—N, which represents the center of gravity or neutral axis of the section. As a result of experimentation, I have found a high tension stress at the point G and a relatively low compression stress at H. Knowing the tensile stress due to the truss action alone, as well as the total measured stresses at points G and H, it is possible to locate a point where, if an imaginary force equal to the total truss tension was assumed to act, it would produce the stress as found by measurement at point G and at point H. A series of these points being determined, a line M—E is drawn, which line I choose to call the imaginary tension force line. The distance between the gravity axis and the tension force line at any section of the tension element 16 is a measure of the bending stress at that point. If it is possible to design the casting so that the gravity axis and tension force line coincide, there will be no bending stresses in the member.

In side frames made heretofore, the gravity axis and tension force line have not even approximated coincidence, and accordingly

bending stresses of considerable magnitude have been developed, which in time have caused fracture of the castings at one or more points. As a result of an exhaustive study and comprehensive experimentation, I have discovered that the defect in casting side frames lies in the improper distribution of stresses or more particularly in not properly connecting the main tension and compression members of the side frame.

While heretofore it has been common to make the side frame tension and compression members U-shaped in section, the web portions or backbone of these members have never been connected directly to each other to properly transmit stresses in direct lines, and in lines along which the stresses should properly extend. In designs heretofore employed, the stresses at certain points have been improperly transmitted through the side walls of the tension and compression members in an effort ultimately to reach a connecting point between the tension and compression members. Such designs, however, have not been satisfactory and in some cases have proved fatal.

To overcome the objectionable features of such designs, such as concerted and excessive bending stresses in different parts of the frame and the improper distribution of stresses, I have provided a construction in which the gravity axis and tension force line of the tension member more nearly or substantially coincide and whereby the stresses are transmitted in direct lines in and between the truck side frame tension and compression members.

Referring particularly to Fig. 10, which shows my improved side frame in section, it will be noted that the web 17 of the tension member 13 is continuous with the upper wall of the beam section 15 from a point inwardly beyond the columns 14 to the compression member 12, and extends in a straight line up through the box section 19 over the associated journal box openings and is connected directly to the web of the compression member at 18 over the ends or points S of support of the side frame. In this way the tension in element 16 of the tension member is exerted at a point considerably above the longitudinal central axis of tension element 15, this eccentric pull materially decreasing the deflection of beam element 15 and decreasing the compression at A in the upper part of beam element and decreasing the tension at B in the lower part of the same element. It necessarily follows that bending stresses are greatly decreased at G and K, and, as a matter of fact, such bending stresses are practically neutralized or balanced by having the tension member web 17 at the inside of the frame and directly connecting said web to the web of the compression member

at the point 18 at each end of the frame. In other words, the gravity axis and the force tension line more nearly coincide and particularly so at the points (line C—D) where 5 the inclined tension elements 16 meet the beam element 15, as shown in Fig. 10. These conclusions are based upon actual figures obtained in extensive experimental work and testing operations.

- 10 The beam portion 15 of the tension member is made in a box shape having a top, bottom and two sides for increasing the strength of the section. It will be noted also that each of the ends of the side frame over the 15 journal boxes is greatly reinforced against bending stresses by having three superimposed webs; namely, the webs of the tension and compression members and the web forming the upper wall 20 of the pedestal jaw. 20 The inclined tension member portions are U-shaped in section. For the reasons given, the main web 17 is at the upper or inner side of said tension member, with the channel opening formed between the two side walls 25 on the lower and outer side.

I claim:

1. A truck side frame including tension and compression members and columns therebetween all cast in a single piece whereby 30 and wherein the bending stresses ordinarily would be greatest and excessive at the upper side of the tension member directly outwardly from the columns and at the under side of said tension member directly inwardly 35 from the journal box portions, said tension member being channel-shaped in section and having its web at the upper side of the tension member to distribute the tension stresses in the tension member in a manner to reduce 40 the bending stresses at the points mentioned.

2. A truck side frame including tension and compression members and column members all cast in a single piece whereby and wherein the bending stresses ordinarily 45 would be greatest and excessive at two points spaced along the length of the tension member and on different sides thereof, said tension member being channel-shaped in section and having its web at the upper side of the 50 tension member to distribute the tension stresses so that the greater part thereof are exerted through the upper web side of the tension member to reduce the bending stresses at the points mentioned.

- 55 3. A truck side frame including tension and compression members and column members all cast in a single piece whereby and wherein the bending stresses ordinarily 60 would be greatest and excessive at the upper side of the tension member directly outwardly from the columns and at the under side of the tension member directly inwardly from the journal box portions, said tension member having a web at the upper

side and continuous from a point between 65 the columns and the compression member whereby the tension stresses in the tension member are transmitted primarily through the upper web side of the tension member to reduce the bending stresses at the points 70 mentioned.

4. A truck side frame including tension and compression members and columns therebetween all cast in a single piece whereby and wherein the tension stresses ordinarily would be greatest and excessive at the under side of the tension member between the columns, at the upper side of the tension member directly outwardly from the columns and at the under side of the tension member directly inwardly from the journal box portions, said tension member being channel-shaped in section and having its web at the upper side of the tension member whereby the tension stresses in the tension member are transmitted primarily through the upper web side of the tension member to counteract and reduce the tension at the points of greatest tension mentioned.

5. A truck side frame including inclined 90 tension and compression members and bolster column members all cast in a single piece whereby and wherein the bending stresses ordinarily would be excessive at points at the upper side of the tension member directly 95 outwardly from the columns and at the under side of the tension member directly inwardly from the journal box receiving portions, said tension member being constructed with its metal arranged in a manner whereby the tension stresses will be so distributed 100 as to reduce the bending stresses at the points mentioned.

6. A truck side frame including integrally formed tension and compression members 105 both U-shaped in section, the tension member having inclined portions, the webs of which are continuous throughout the inclined portions, extend through the box section over the journal box openings, and are connected 110 directly to the web of the compression member whereby bending stresses in the inclined portions of said tension member are reduced.

7. A truck side frame including tension and compression members and column members therebetween all cast in a single piece whereby and wherein the tension stresses ordinarily would be greatest and excessive at the under side of the tension member between the columns, at the upper side of the tension member directly outwardly from the columns and at the under side of the tension member directly inwardly from the journal receiving portions, said tension member between the columns being walled on all sides 120 and the portions outwardly from the columns being channel-shaped in section and each having its web at the upper side of the

tension member whereby the tension stresses in the tension member are carried in a manner to counteract and reduce the tension at the points of greatest tension mentioned.

- 5 8. A truck side frame including tension and compression members cast in a single piece wherein the bending stresses ordinarily would be excessive at the upper side of the tension member directly outwardly from the 10 columns and at the under side of the tension member directly inwardly from the journal box receiving portions, said tension and compression members both being U-shaped in section and having their webs at their 15 upper sides, respectively, for reducing the bending stresses in said tension member.

9. A truck side frame including tension and compression members and column members therebetween all cast in a single piece 20 whereby and wherein tension stresses ordinarily would be greatest and excessive at spaced points on opposite sides of the tension member along the length thereof, said tension member between said column members being of a box-like structure and outwardly beyond said column members being 25 channel-shaped in section and having the web at the upper side of the tension member for distributing the tension stresses in a 30 manner such that said tension stresses are reduced at the points of greatest tension mentioned.

10. A truck side frame including integrally formed tension and compression 35 members both U-shaped in section, the tension member having inclined portions the webs of which are continuous throughout the inclined portions and are connected directly to the web of the compression member 40 approximately over the center line of the journal boxes whereby stresses in the in-

clined portion of the tension member are reduced.

11. A truck side frame including integrally formed tension and compression 45 members both U-shaped in section, the tension member having inclined portions the webs of which are continuous throughout the inclined portions and are connected directly to the web of the compression member 50 approximately over the center line of the journal boxes whereby stresses in the inclined portion of the tension member are reduced, there being an additional web immediately over each journal box to resist 55 local bending stresses directly inwardly from the journal box receiving portion.

12. A truck side frame including tension and compression members cast in a single piece, the middle portion of the tension 60 member, at its point of juncture with tension member portions extending outwardly therefrom, having a neutral axis below the neutral axes of said outwardly extending tension member portions whereby bending 65 stresses in the tension member are minimized.

13. A truck side frame including tension and compression members cast in a single piece, the middle portion of the tension 70 member being of a box-like structure and the portions extending outwardly therefrom being channel-shaped in section with the web at the upper side whereby the neutral axis of the middle portion at its points of 75 juncture with the channel-shaped portions is below the neutral axes of said channel-shaped portions whereby the bending stresses in the tension member are minimized.

Signed at Chicago, Illinois, this 11th day 80 of December, 1919.

GEORGE G. FLOYD.
